UNITED STATES PATENT OFFICE.

PAUL H. LUNDMARK, OF CHICAGO, ILLINOIS.

DESIGN FOR CHRISTMAS TREE HOLDER.

Application filed October 23, 1922. Serial No. 4,058. Term of patent 3½ years.

To all whom it may concern:

Be it known that I, PAUL H. LUNDMARK, a citizen of the United States, residing at Chicago, in the county of Cook and State of Illinois, have invented a new, original, and ornamental Design for Christmas-Tree Holders, of which the following is a specification, reference being had to the accompanying drawings, forming part thereof.

The figure is a perspective view of a Christmas tree holder showing my new design and comprising a base supported upon downwardly and outwardly diverging legs and having superposed thereon a bowl in which the lower end of a tree trunk may be secured.

I claim:

An ornamental design for Christmas tree holders substantially as shown and described.

PAUL H. LUNDMARK.
